(57) **CLAIM**

The ornamental design for the dice tray, as shown and described.

DESCRIPTION

FIG. 1 is an isometric view of a dice tray showing my new design.

FIG. 2 is a left-side elevational view thereof.

FIG. 3 is a right-side elevational view thereof.

FIG. 4 is a front elevational view thereof.

FIG. 5 is a rear elevational view thereof.

FIG. 6 is a top plan view thereof; and,

FIG. 7 is a bottom plan view thereof.

Any broken lines in the drawings are for illustrative purposes only and form no part of the claimed design.
